CLAIM

The ornamental design for an alien face tool, as shown.

DESCRIPTION

FIG. 1 is a plan view of the top and bottom sides, which are mirror images of each other, of my new design for an alien face tool.

FIG. 2 is a right side plan view of the tool shown in FIG. 1.

FIG. 3 is a left side plan view of the tool shown in FIG. 1.

FIG. 4 is a front side plan view of the tool shown in FIG. 1.

FIG. 5 is a rear side plan view of the tool shown in FIG. 1.

FIG. 6 is a top perspective view of the tool shown in FIG. 1.

FIG. 7 is a plan view of the top and bottom sides, which are mirror images of each other, of an alternate embodiment with an attachment nub of my new design for an alien face tool.

FIG. 8 is a right side plan view of the tool shown in FIG. 7.

FIG. 9 is a left side plan view of the tool shown in FIG. 7.

FIG. 10 is a front side plan view of the tool shown in FIG. 7; and,

FIG. 11 is a rear side plan view of the tool shown in FIG. 7.
